UNITED STATES PATENT OFFICE.

JACOB K. DIMMICK, OF NEWPORT, KENTUCKY.

APPARATUS FOR FORMING MOLDS FOR CASTING METAL PIPE.

SPECIFICATION forming part of Letters Patent No. 317,101, dated May 5, 1885.

Application filed May 28, 1883. (No model.)

To all whom it may concern:

Be it known that I, JACOB K. DIMMICK, a citizen of the United States, residing at Newport, in the county of Campbell and State of Kentucky, have invented certain new and useful Improvements in Apparatus for Forming Pipe-Molds, of which the following is a specification.

My invention consists in combining, with a frame or flask for molding a "former" of such shape that its withdrawal packs the mold-sand tightly, accessory mechanism which permits the sand to be filled in the top of the flask before the former is started, and thereafter guides and directs said former while allowing it a continuous uninterrupted motion through and exit from said flask and from the completed mold, and in such further specific combinations as are hereinafter set forth and 20 claimed.

The accompanying drawing is a vertical section of apparatus embodying and adapted to the carrying out of my invention.

A represents the flask, which may be the same as heretofore patented by me—to wit: in Letters Patent No. 253,854, granted on the 21st day of February, 1882—or of any other construction usual in this class of work.

B, C, D, and E are the four sections or reaches of the former, either rigidly secured together or integral with each other; F, a guide ring or sleeve centered in place by the bell-pattern G, which has an axial bore for the purpose, of diameter very slightly exceeding the external diameter of said ring, the latter being prevented from falling through the pattern and to the bottom of the flask by a peripheral flange about its crown, but otherwise retained in place by its own weight.

H is the upper plate, which is clamped to the flask at I, and has shoulders J countersunk in the bell-pattern to hold the latter rigidly in place and prevent "wabbling," but is centrally apertured for the passage of the guide-ring when the latter is lifted from its seat.

The upper reach or section, B, of the former has an external diameter just sufficiently less than the internal diameter of the guide-ring, through which it passes, to allow it to slide 50 freely therein. The next lower reach or sec-

tion, C, increases regularly in diameter until at its foot it is substantially the same as the external diameter of the guide-ring. The third reach or section should have a space between it and the walls of the central or axial bore 55 through the bell-pattern, averaging an eighth of an inch to the entire diameter of said bore, and the last reach or section, E, is intended to fit into an opening in the bottom of the flask for the purpose of centering and steadyng the 60 former.

It will be seen that the former is thus retained in position by the guide-ring and the opening or seat at the bottom of the flask. The smaller reach or section of the former 65 engages the amount of sand received in the mold, while the flaring head measures the interior size of the mold, and by its longitudinal movement through the flask, when being withdrawn, packs the sand. The amount of flare to the 70 head of the former determines the closeness with which the mold is packed.

I make the smaller section of the former of such size relative to the larger section and the flask as will secure the compression of the 75 sand practically one-third its bulk—that is, the space left for sand around the larger part of the former is about two-thirds that around the smaller part. This may be varied according to the compression required in the mold 80 and the character of sand used; but the proportion given is approximately the best.

The mode of forming the molds is as follows: When the flask and the former are in position, as shown in the drawing, sufficient 85 sand is placed in the flask to fill it, when properly rammed slightly above the upper end of the flaring section C of the former, or, say, ten inches in a twelve-foot mold, proportioning it in such manner that the unrammed sand will 90 be properly compacted in the subsequent operations. This sand, thus placed, is rammed in the ordinary way. The remainder of the flask is then filled with sand, without ramming, up to the neck of the bell-mouth, or to 95 the top, a seat for the bell-mouth pattern being in the latter case roughly shaped by hand. The bell-mouth is placed in position and sand filled in and rammed about it, and the top plate put on and locked by keys or cotters. 100

Then, the necessary power being applied at the ring *a*, which is strongly secured to the upper section, *B*, of the former, or in any other convenient manner, the former is withdrawn from the flask, sliding through the sleeve or guide-ring, which remains in place until the reach or section *C* comes in contact with it and controls the movement of the former in a path parallel with the walls of the mold to be made. When the section *C* reaches the guide-ring, it lifts said ring up through the central bore of the bell-pattern in which it has been seated. Continuing the withdrawing of the former, the lower reach or section, *D*, next enters this central bore and passes through. Now, as the surface of the reach *C* is equally pressed upon by the mold-sand at every point and tapers upward, drawing this section upward compresses tightly together the particles of the sand and renders the surface of the mold smoother, and packs it more uniformly than can be done by any ramming of the mold-sand about the former by hand or by machine—such hand or machine ramming unavoidably compressing the mold-sand in some places more than in others, thus leaving the surface of the mold uneven and liable to expand unequally when exposed to the heat and pressure of the cast, and liable to the formation of blow-holes. By the time the portion *C* reaches and lifts the guide-ring the mold has been formed for the most of its length. As the guide-ring rises (still keeping the former perpendicular) it is itself prevented from wabbling by the interior walls of the bell-pattern, and the distance from the lower end of the guide-ring in its original position to the upper extremity of the bell-pattern being greater than the length of the section *C*, it will be seen that section *D* will have entered the central bore of the pattern before the guide-ring leaves it, thus entirely obviating any irregular movement from side to side.

It is obvious that other modes of guiding the former or of withdrawing the compressor-head may be adopted without departing from the essential features of my invention. For instance, the head of the former may, without altering its shape or office, be made to slide on the smaller portion or section, and the smaller section subsequently be withdrawn. So long as the head serves to

measure the interior dimensions of the mold and its tapering face to compress the sand when it is withdrawn, while the smaller section of the former determines by its relative size the amount of sand to be introduced and the degree of compression to be given it, and a gravitating or equivalently removable guide-ring centered in the axial bore of the bell-pattern is employed, the leading features of my invention will be more or less perfectly employed.

I claim as my invention—

1. The combination, substantially as described, with a movable former constructed with a first section or length of uniform diameter, a second section gradually increasing in diameter, and a third section of diameter uniform with the greatest diameter of the preceding, of a bell-pattern having a central bore of such diameter as to permit the passage of the entire former loosely, and a guide fitting into said bore and acting to center and direct the lesser section of the former with respect to the bell-pattern until the larger section enters the bore thereof.

2. The combination, substantially as described, with a flask and compressing-former, having substantially the outline set forth, which former is capable of being drawn upward through said flask to pack and compress the sand against its walls, of a guide-ring for the narrower section of said former, resting in place at the top of the flask, and adapted to be automatically released and lifted by the continuing motion of the former when the enlarging section thereof comes in contact with it.

3. The combination, substantially as described, with the former and the guide-ring, of a bell-pattern having an axial bore in which the guide-ring is centered and restrained from lateral motion, and through which it can pass when raised by the flaring section of the former.

4. The combination of the flask *A*, the enlarging former, the guide-ring *F*, the bell-pattern *G*, and the clamping-plate *H*, as and for the purpose set forth.

JACOB K. DIMMICK.
